UNITED STATES PATENT OFFICE.

WALTER L. HARPER, OF BIRMINGHAM, ALABAMA.

ENVELOP.

1,292,769.

Specification of Letters Patent. Patented Jan. 28, 1919.

Application filed May 20, 1918. Serial No. 235,597.

To all whom it may concern:

Be it known that I, WALTER L. HARPER, a citizen of the United States, residing at Birmingham, in the county of Jefferson and 5 State of Alabama, have invented new and useful Improvements in Envelops, of which the following is a specification.

This invention relates to envelops, the object being to provide a combined envelop 10 and wage statement sheet, whereby each individual employee may obtain a statement of his standing with his employer.

A further object of the invention is to provide an article of this character by means 15 of which two records of the earnings, stoppage, etc., of an individual may be simultaneously made, thereby lessening the liability of error and providing a record for both the individual and his employer, the construction being such as to permit of conveniently 20 detaching one record without impairing the usefulness of the novelty as a receptacle.

To this end the invention includes the following novel construction and arrangement 25 of parts, to be hereinafter more fully described and illustrated in the accompanying drawings, in which:—

Figure 1 is a plan view of a blank from 30 which the envelop is formed, looking at the side of the blank containing the indicia;

Fig. 2 is a view of the opposite side of the blank; and

Fig. 3 shows a complete envelop looking at the back panel.

Referring to the drawings in detail wherein like characters of reference denote corresponding parts, the envelop is shown as including a front panel 10 and a back panel 11, the latter being secured to the front panel 40 along one of its longitudinal edges and adapted to be folded on the dotted line 12 in the formation of the envelop. The panel 11 is formed with a longitudinal flap 13 and a transverse flap 14, one side of which is 45 provided with suitable adhesive material by means of which the panels are secured together. Secured to the front panel 10 is a sealing flap 15, which is provided with suitable adhesive material as shown at 16 for the purpose of sealing the envelop.

Formed preferably on the sealing flap 16 is an extension 17 which is separated from

the sealing flap by a perforated line 18, this line providing for conveniently detaching the extension 17 for a purpose hereinafter 55 apparent. The extension 17 is adapted to form a record slip by means of which the earnings and deductions of each individual employee may be recorded and filed and for this purpose one face of the extension 60 17 is provided with suitable indicia 19. The blank from which the envelop is formed is also imprinted or otherwise spaced preferably upon the back panel 11 indicia 20 similar to the indicia 19 of the extension 17. 65 The relative positions of the indicia 19 and the indicia 20 are such that when the back panel 11 is folded over to form the envelop, the extension 17 may be folded downwardly so that the indicia thereon will register with 70 the indicia of the back panel 11 and a sheet of carbon paper may be placed underneath the extension and a double record simultaneously made. The extension 17 may be then detached along the perforated line 18 75 and the flap 16 sealed.

The invention is susceptible of various changes in its form, proportions and minor details of construction, for example the positions of the back 11 and extension 17 may 80 be reversed and it is not the purpose of the invention to be limited to the particular disposition and arrangement of parts to be herein shown and described.

Having described the invention, what is 85 claimed is:—

An envelop made from a single piece of material of substantially L-shaped formation, said material being divided into a front panel having along one side edge a 90 panel to form the back of the envelop, the first mentioned panel having a sealing flap along one edge thereof, the second mentioned panel having sealing flap along one side and one edge respectively to join the 95 front and back and an extension formed on the first mentioned sealing flap, said extension and front panel containing duplicate indicia which is adapted to be brought into register before the envelop is formed and 100 thereafter detached to provide separate duplicate records.

In testimony whereof I affix my signature.
WALTER L. HARPER.
